UNITED STATES PATENT OFFICE

153,805

DESIGN FOR A PORTABLE SIGNAL LIGHT FOR MOTOR VEHICLE OR SIMILAR ARTICLE

Frederick K. Hussey, New York, N. Y.

Application May 18, 1948, Serial No. 146,433

Term of patent 14 years

(Cl. D72—1)

To all whom it may concern:

Be it known that I, Frederick K. Hussey, a citizen of the United States, residing in the Borough of Manhattan, city, county, and State of New York, have invented a new, original, and ornamental Design for a Portable Signal Light for Motor Vehicle, or Similar Article, of which the following is a specification, reference being had to the accompanying drawing, forming part thereof.

Fig. 1 is a perspective view of a portable signal light for motor vehicles, showing my new design;

Fig. 2 is a plan view of the same;

Fig. 3 is a front elevation of the same; and

Fig. 4 is a rear elevation of the same.

The dotted lines shown in Fig. 1 are for illustrative purposes only. The diagonal lines on the flat element of Fig. 1 represent a color designation.

I claim:

The ornamental design for a portable signal light for motor vehicle, or similar article, substantially as shown and described.

FREDERICK K. HUSSEY.
